PAINT FUNNEL-SCRAPER

James Lee Akers, Anneslie, Md.

Application August 10, 1936, Serial No. 95,305

3 Claims. (Cl. 220—90)

This invention refers to paint brushes and more particularly to a device applicable to a paint container for the purposes of scraping paint off brushes and diverting same back to the container. It has among its objects to provide a device of this nature that will scrape off paint on the sides and edges of a paint brush and divert same towards a central location of the device; also to have the device arranged whereby it may be used as a funnel; and where used as a funnel to cooperate with the construction of the container and hold itself securely thereon. Another object is to provide a construction that will enable the device to be used under the practical conditions arising under usual circumstances. A further object is to have the funnel arrangement such that it will flow the dripping paint or liquid directly into the central part of the container, to be saved, rather than run down the outside walls of the same to be wasted. A still further object is to have the device such that it may be snapped on, into place, and secure itself resiliently into position on the container and become as tight thereon as its cover would be, as well as to prevent the top of the container becoming vitiated by sufficient paint to prevent the cover going back on properly. The device in general, also serves to keep the container clean on the outside and top where the cover goes on. It also has the particular feature of enabling the paint, even in a full can to be stirred until properly mixed, without spilling. Even if the paint runs up into the funnel scraper, it will not leak through the connection joint to the outside of the can. It avoids the practice of having to half empty a new full can of paint to mix it.

Various methods have been used for cleaning off brushes so the paint will drain back off the scraper, but such usually permits the paint to drip down and gather on the outside wall of the container, and spoil surfaces on which the containers are resting. In this invention the device is made after the form of funnel with its restricted central portion bent or formed to fit into the cover groove of the conventional form of container at the mouth portion where the cover is engaged and locked, when closed on same. In order to have an arrangement for cleaning brushes on all sides and without requiring the use of the top rim for the purpose, the device is provided with embossings that project out sufficiently to permit them to scrape and carry excess paint off the brush when the same is drawn against them. The upper rim portion of the device is rounded and wired to

stiffen and strengthen it. When sufficient paint has been removed from the container, the funnel scraper is lifted off and the cover put on in its place, leaving the paint can in a clean condition ready to be used again.

In the construction shown in the drawing, by way of example:—

Figure 1 is a side elevation of a funnel-scraper embodying this invention, with a portion partly in section, as shown, attached to a container,

Figure 2 is a plan view of the funnel-scraper by itself, and

Figure 3 is a side elevation of the funnel-scraper of Figure 2.

Similar reference characters refer to similar parts throughout the drawing.

In the drawing, 1 represents a conventional form of tin can container for paints with its upper cover holding groove portion or top ring 2 indented at 3 to receive the snap-on cover 20 within the area of the top adjacent to the periphery of the container. A funnel-shaped member 4 having its upper and wider portion 5 rolled and wired, preferably as indicated, serves as the mouth of the funnel scraper. Its lower 25 and restricted portion 6 is provided with bent back U-shaped rim 7 designed to fit in closely in the indentation or cover groove 3 of the container and position the funnel scraper rigidly above and over the container as shown. A flat 30 lip flange 8 extends radially from the bent back U-shaped rim 7 to stiffen the same and also cover the upper portion of the can top peripheral rim, and close all opening to the said indentation or cover groove exteriorly. This flange is arranged 35 however, to fit within the bead rim 10 of the can.

The funnel scraper is formed like a funnel in general appearance, with its walls 11 slanting towards the central portion of the can, and tending to flow any paint falling on the interior surface of the walls into the can. A series of scraper embossings extend along the surfaces in angular directions as indicated in the figures, and have their edges 13 and 14 bevelled off. The lower series of embossings extend over beyond the edges 14 of the upper series, in order to catch the paint dripping down and make a single river from all embossings immediately above.

In the operation of the device, assuming that 50 the funnel scraper is placed in position on a suitable container, the user, places the paint brush in the container and draws it out. As it passes through the funnel scraper, he "rolls" 55 the brush, by brushing it spirally upwards, cross-

ing the embossings and cleaning the excess paint off the brush. The excess paint is caught on the under side of the embossings and flows towards their lower bevelled end portions from where it drops downwardly to the bottom orifice of the funnel scraper and passes into the container. The spacings between the embossings enable the paint to flow freely down. The paint that comes off above the embossing is also caught on the 10 embossings and flows down same diagonally to the spacings, where it joins the other paint streams and flows back into the container. The sides of the brush may be cleaned off in a similar manner. The funnel scraper over-laps the paint 15 container and prevents the paint from falling on same, as it does when taken from a container without this device. The usual method of cleaning the paint on the cover opening of the can causes paint to fill up the indentation 20 in which the cover sets. When this cover is put on after being used without the funnel scraper, it becomes cemented in as the paint dries. It also causes the user to soil his hands or the surfaces on which the container rests, because the cover will "spill out" the extra paint 25 in the indentation or cover groove.

The funnel scraper is readily removed at any time, because the upper portion of the funnel provides ample grasping surface, as well as lever- 30 age. All the paint caught by the funnel returns to the inside of can, preventing the groove from filling with paint. When the funnel scraper has been removed, it leaves the cover groove completely clean and free from paint. In other words, 35 it has removed from the use of the paint can, the usual conditions of spilled or dripping paint and a dirty container.

While the material used for the scraper is preferably metal, it can also be made of oiled paper, 40 fiber, or similar substances that will be an advantage in general and may have features of economy or convenience. Also it is not desired to limit this application for patent to this particular form of construction, or in any other way otherwise 45 than limited by the prior art, as it is appreciated that other forms using the same principles could be made that would come within the scope of the appended claims.

Having thus described the invention, what is 50 claimed is:

1. In combination with a conventional paint container having a peripheral groove formed in its top ring for taking and holding a snap-on cover, a paint funnel for mounting in the said groove and extending above the container having an upper widened-mouth portion with converging 55 walls to its lower orifice portion provided

with bent-back U-shaped peripheral rim adapted to fit into the said peripheral groove with a radially extending flat-lip flange positioned over the top ring and close ingress to the groove, the said funnel being disposed with its walls and parts all exterior to the interior of the container, the walls of said funnel being provided with V-shaped scraper embossings angularly placed internally extending therefrom to hold a paint brush up from the orifice portion and to direct scrapings 10 of paint downwardly towards the orifice of the funnel.

2. In combination with a circular conventional paint container having a cover-receiving groove in its top ring, a snap-on paint funnel with frustromatically formed walls with its upper mouth portion enlarged and spaced substantially above the container and its lower orifice portion disposed and held in the said groove, said lower orifice portion being restricted and having a bent-back U-form ring adapted to fit tightly within said groove and keep the inner surface of the funnel wall outside and above the area of the central opening in said top ring, a flat ring flange connected with the U-form ring and extending back over the top ring of the container, V-shaped projections extending arcuately above the wall, internal surfaces of the funnel in variable planes and spaced away from each other above and at the end portions to provide ridges to rest and spread the bristle portion of a brush thereon and to provide grooves exteriorly in the wall of the funnel for facilitating handling thereof, substantially as described.

3. In combination with a circular conventional paint container having a cover-receiving groove in its top ring, a snap-on paint funnel with frustromatically formed walls with its upper mouth portion enlarged and spaced substantially above the container and its lower orifice portion disposed and held in the said groove, said lower orifice portion being restricted to partially obstruct the passage of paint brushes therethrough and having a bent-back U-form ring adapted to fit tightly within said groove and keep the inner surface of the funnel wall outside and above the area of the central opening in said top ring, a flat-ring flange connected with the U-form ring and extending back over the top ring of the container, embossings formed in the walls extending inwardly into the funnel with apexed surfaces and spaced apart and angularly disposed to divert paint scraped off brushes by them in predetermined directions and collective streams to the orifice and opening in the container.
